UNITED STATES PATENT OFFICE

GEORGE B. NICHOLS, OF AKRON, OHIO, ASSIGNOR TO THE FIRESTONE TIRE & RUBBER COMPANY, OF AKRON, OHIO, A CORPORATION OF OHIO

INFLATION APPARATUS

Application filed April 13, 1929. Serial No. 354,803.

In the art of making inner tubes it has been customary to test the finished tubes at the factory for leaks by inflating the tubes and depressing them under water. These tests in the past have been somewhat hazardous in that the operatives inflating the tubes have depended upon guess-work only to determine the degree of inflation. Accordingly fair tests have not always resulted in that if the pressure in the tire is too low, small leaks affecting later service of the tube will not be detected.

The invention has for its object the provision of a simple means for inflating hollow rubber articles and particularly inner tubes, quickly and without attention to pressure gauges or the like to a desired degree of inflation such as required for example in order to make fair and uniform tests of completed inner tubes at a factory before shipment.

The foregoing and other purposes of the invention are attained in the inflation apparatus illustrated in the accompanying drawings and described below. It is to be understood that the invention is not limited to the particular form thereof shown and described.

Of the accompanying drawings,

Figure 1 is a front elevation of apparatus embodying the invention as employed in the manufacture of inner tubes;

Figure 2 is a section on line 2—2 of Figure 1;

Figure 3 is a diametrical section through the inflation valve; and

Figure 4 is a diametrical vertical section through the automatically controlled air supply valve and connection.

Referring to the drawings, the numeral 10 designates a suitable support such as a bar on which is mounted a bracket 11 supporting arms 12, 12 radiating upwardly therefrom and outwardly offset at 13 to provide shoulders, the upper ends of arms 12 preferably being outwardly flared as at 14 so as not to injure an inner tube inserted in the apparatus.

A supply valve housing 15 is mounted on bar 10 and has a bracket 16 mounted on its upper surface on which an upwardly di-

rected arm 17 is pivoted as at 18 rearwardly opposite the arms 12, arm 17 being rearwardly offset at 19 to provide a shoulder and preferably being outwardly flared at its upper end also as at 20.

Arms 12 and 17 are thus adapted to receive and support an inner tube 21 to be inflated therebetween on shoulders 13 and 19, arm 17 being normally held in a substantially vertical position by means of a spring 22 between bracket 16 and said arm holding the portion of said arm below pivot 18 in contact with the valve stem 23 of a valve 24 in casing 15, the valve 24 normally being held in an open position by arm 17, the action of which is limited by a sleeve 25 adapted to abut the end of valve casing 15.

An under pressure is supplied to the valve casing 15 by a duct 26 and through the valve 24 to a duct 27 connected to an inflation check valve 28 of a known type, a conical socket member 29 being arranged on said valve to guide and hold the valve 30 of an inner tube 21 mounted over shoulders 13 and 19 between arms 12 and 17 (Figures 1 and 2).

It will be apparent that when an inner tube is thus mounted in the apparatus air under pressure will be supplied thereto which will inflate the tube to circular form 80 in section as illustrated in dotted lines in Figure 1, the sectional diameter of which will increase as the pressure in the tube rises. This swings the upper end of arm 17 rearwardly, and gradually releases pressure of the lower end of arm 17 on the valve stem 23 whereby valve 24 gradually closes under the pressure of the air supply. The movements of arm 17 and valve 24 are so coordinated that when a predetermined expansion of the inner tube is reached the valve 24 will close shutting off the supply of air to the inflation valve 28. The tube 21 may now be removed for testing and another tube to be inflated mounted in the apparatus.

It will, of course, be understood that the apparatus is not limited to the specific use set forth and that modifications thereof may be resorted to for this or other purposes 100

without departing from the spirit of the invention or the scope of the appended claims.

What is claimed is:

- 5 1. Inner tube inflation apparatus comprising opposed arm members having shoulders thereon for supporting an inner tube therebetween, one of said members being pivoted to swing toward and from the other, an inflation valve arranged between said arms for cooperation with the inner tube valve, a supply valve connected to the inflation valve, means normally urging the pivoted arm member toward the opposite
- 10 15 arm member, said pivoted arm member cooperating with said supply whereby it is normally held open, said supply valve being adapted to close when said pivoted arm member is moved away from the opposite
- 20 25 arm member by expansion of the inner tube a predetermined amount.

2. A device for use in inflating hollow articles comprising relatively movable members adapted to receive a hollow article therebetween, means normally urging the members toward each other adapted to permit movement of the members apart by expansion of the hollow article therebetween, an inflation valve adapted to be connected to the article, and a supply valve connected to the inflation valve and normally held open, said valve being adapted to be closed by relative movement of said members apart by a predetermined expansion of the hollow article.

In witness whereof, I have hereunto affixed my signature this 10th day of April, 1929.

GEORGE B. NICHOLS.
